UNITED STATES PATENT OFFICE.

WALTER M. SCHWARTZ, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Application filed June 28, 1921. Serial No. 480,953.

To all whom it may concern:

Be it known that I, WALTER M. SCHWARTZ, a citizen of the United States, residing in Philadelphia, Pennsylvania, have invented 5 certain improvements in Driers, of which the following is a specification.

My invention relates to certain improvements in driers, or stove rooms, for drying porcelain, china, and other ceramic wares, 10 but it will be understood that the invention can be used for drying other articles and materials without departing from the main features of the invention.

One object of the invention is to construct 15 a drier so that the feed end of the drying chamber will be cooler than the delivery end.

A further object of the invention is to provide a fan, which is located near the delivery end of the drier, and to locate the heating pipes above the fan so that the air in circulation will pass down through the material at the delivery end of the drying chamber and will circulate upwards at the 25 feed end.

A still further object of the invention is to provide means to prevent the inrush of cool air through the feed and delivery openings.

These objects I attain in the following manner, reference being had to the accompanying drawings, in which:

Fig. 1 is a longitudinal sectional view of my improved drier;

Fig. 2 is a transverse sectional view on the line 2—2, Fig. 1;

Fig. 3 is a longitudinal sectional view of a modified form of drier;

Fig. 4 is a transverse sectional view on the line 4—4, Fig. 3; and

Fig. 5 is a view illustrating another modification of the invention.

Referring to the drawings, 1 is the casing of the drier, which may be of any type desired. 2 is the feed opening through which the articles are placed in the drier. 3 is the delivery opening from which the articles are taken from the drier. At or about the center of the drier, in the present instance, is a vertical partition 4, which is connected to a horizontal partition 5 located some distance from the top of the drier at the delivery end and terminates some dis-

tance from the bottom of the drier. In the horizontal partition 5 is an opening 6 in which is a circulating fan 7 mounted on a vertical shaft 8 extending through the roof of the drier and on which is a belt pulley, or sprocket wheel 9, by which the fan is driven. The partition 4 divides the drying chamber into two compartments 10 and 11. At the feed end is a partition 12 located in front of the feed opening and at the delivery end is a similar partition 13 in front of the delivery opening. 16, 16 are short partitions above and below the two openings. The trays 14, which are carried by the endless chain conveyer 15, pass between the partitions and act to prevent the inrush of air through the feed and delivery openings.

The trays may be of any form desired, depending upon the character of the material and the shape of the articles to be dried. In the present instance, the trays 14 extend from side to side of the conveyer 15 and are pivotally connected to the chains of the conveyer 15, which pass around wheels 22 in the upper portion of the compartment 10 and under wheels 17 in said compartment, and around wheels 18 located directly under the partition 4 and around wheels 19 in the upper portion of the compartment 11 under the fan 7 and under a wheel 20 in the lower portion of said compartment. The guide wheels 21, at each end of the drier near the floor, guide the chains from the delivery end to the feed end of the conveyer. The chambers 10 and 11, in the present instance, extend to the bottom of the conveyer, although a horizontal partition may be located some distance from the bottom when it is desired to separate the return run of the conveyer from the run passing through the drying chambers.

Heating pipes 23 are located above the partition 4 in the path of the air in circulation and additional heating pipes 24 may be located on the opposite side of the fan, if desired. By this arrangement, the air is reheated before it flows into the compartment 11 so that the material being conveyed through said compartment is subjected to a greater degree of heat than the material in the compartment 10.

In Figs. 1 and 2, the partition 4 is shown located at the center of the drying chamber

so that the chamber 10 is of the same length as the chamber 11. In Figs. 3 and 4, a partition 4^a is shown located close to the delivery of the drier and two small fans 7^a are used, the fans being located side by side, as illustrated in Fig. 4. Heating pipes 23^a and 24^a are arranged, as shown.

By this construction, the compartment 10^a is considerably larger than the compartment 11^a and the material being dried is subjected to warm air while in the compartment 11^a for considerably less time than it is subjected to the air not quite so warm in the compartment 10^a. The location of 15 the vertical partition in the drier will depend upon the material being dried, but, in any case, the space in which the primary drying is accomplished should be as great, and, in many instances, greater, than that 20 in which the drying is completed at a higher temperature.

In Fig. 5 is shown a modification in which a circulating fan is located at the feed end of the drier, in addition to the fan at the 25 delivery end, and a partition is so arranged as to cause a circulation of air at the feed end independently of the circulation of air at the delivery end. In this case, the air in circulation at the feed end of the drier 30 is heated to a less degree than that at the delivery end or, it may be air under normal temperature, if desired.

The operation is as follows,—referring to Figs. 1 and 2. The material to be dried 35 is placed on the trays 14 through the opening 2 and as the conveyor travels in the direction indicated by the arrows the material is subjected to the up currents of air in the compartment 10, the air being comparatively cool. The conveyor with the material passes under the partition 4 and into the compartment 11 where it is subjected 40 to the direct action of down currents of heated air, which is caused by the fan 7 to circulate down through the compartment 11 and up through the compartment 10. The conveyor finally passes between the partitions 13 and 16, and when the trays 45 are opposite the opening 3, the material is removed from the tray. The air as it passes from the compartment 10 to the space above the partition 5 is reheated by the steam pipes 23 and 24. By this construction the material passing through the compartment 55 11 is subjected to a greater degree of heat than the material passing through the compartment 10.

I claim:

1. The combination in a drier having a 60 feed opening at one end, and a discharge opening at the opposite end; a drying chamber; a vertical partition dividing the main portion of the chamber into two compart-

ments, but affording communication between the compartments at top and bottom; a horizontal circulating fan above the compartment at the delivery end of the drier, and means near the fan for heating the air so that heated air will be circulated down through the compartment at the delivery 70 end and the cooler air will be circulated upwards in the compartment at the feed end of the drier, and a conveyor arranged to travel through both compartments.

2. The combination in a drier having a 75 feed opening at one end and a discharge opening at the opposite end, of a drying chamber; a vertical partition dividing the main portion of the chamber into two compartments but affording communication between the compartments at top and bottom, the compartment at the feed end of the drier being equal to, or greater than, the compartment at the delivery end; means 80 for carrying material through the drier; a circulating fan located so as to cause a downward circulation in the compartment at the delivery end and an upward circulation in the compartment at the feed end; and means for heating the air in circulation.

3. The combination in a drier having a 85 feed opening at one end and a discharge opening at the opposite end, of a drying chamber; a vertical partition dividing the main portion of the chamber into two compartments, said partition stopping short of the bottom of the drying chamber; a horizontal partition spaced from the casing of 90 the drier and located above the compartment at the delivery end of the drier; said partition having an opening therein; a circulating fan located in the opening; heating pipes in the space above the horizontal partition; an endless chain conveyor having 100 trays; and guide wheels for the conveyor in both compartments of the drier for directing the conveyor in a circuitous path so that the material on the trays will be subjected to up currents of air in the compartment at the feed end of the drier and to down currents of air in the compartment 105 at the delivery end of the drier.

4. The combination in a drier, of a drying 110 chamber; a vertical partition stopping short of the top and bottom of the drying chamber and dividing said chamber into two compartments; means for circulating air in 115 said compartments, the drier having a feed opening at one end and a delivery opening at the opposite end; partitions extending above and below said openings; and trays fitting the spaces between the partitions at each opening and acting to prevent the 120 rush of air through said openings.

WALTER M. SCHWARTZ.
